MANICURING IMPLEMENT

Philip F. Acocella, Brooklyn, N. Y.

Application May 8, 1935, Serial No. 20,313

4 Claims. (Cl. 132—74)

My invention relates to manicuring implements and particularly to a portable power driven implement that is light in weight, easy to handle and operate, low in cost, and yet capable of efficiently and safely performing all manicuring operations.

Heretofore manicuring operations have been performed entirely by hand, which is slow and expensive, although many attempts have been made to utilize power driven machines for this purpose. The machines heretofore have not proven satisfactory for many reasons among which are that they are too heavy, cumbersome and expensive to operate, are dangerous to both the operator and customer, and do not properly perform all operations. Having the requirements of an efficient machine in mind, I have perfected the present invention which overcomes all objections or defects in prior machines and now makes it possible to perform all manicuring operations with a single implement that can be held in one hand to operate upon the nails of the other hand or of a foot of the operator or on a customer without danger of injury and yet do a perfect job of cleaning, trimming, filing, polishing, buffing, pressing back of cuticle, etc.

In the accompanying drawing I have illustrated a preferred form of my invention wherein;

Fig. 1 is a perspective view showing the device in operation.

Fig. 2 is a longitudinal section taken on the line 2—2 of Fig. 1, the motor being shown in elevation.

Fig. 3 is a sectional view on the line 3—3 of Fig. 2.

A housing 10 for an electric motor driven by current from the wires 11 is detachably connected at 12 to one end of a tubular casing or handle 13, which is contracted at its opposite end to form a bearing 14 for the shaft or spindle 15. The spindle is connected at its inner end by a sleeve 16 to the shaft 17 of the motor, and carries the buffer or polisher 18, rotary file 19 and nail cleaner 20. Preferably the spindle is made as shown but it may be supported intermediate its ends in a bearing within the handle 13, and be an integral extension of the motor shaft. The several operating tools 18, 19 and 20 are detachably supported on the shaft, but are rotatable therewith.

The casing 13 has one or more openings 22 affording access to the buffer 18 and similar openings 23 for the file or abrasive element 19. These openings 22 and 23 usually are shorter than the tools 18, and 19 but are of proper design and size to permit ready application of the buffer and file to the nails yet prevent injury to the cuticle or nails through careless operation, as is clearly illustrated in Fig. 1.

60 The nail cleaner 20 may be of any shape or

style desired and it is within the contemplation of the invention that this part will be used in several interchangeable shapes and sizes for purposes other than cleaning, for example, cuticle pushers, orangewood sticks, small buffers, 5 brushes, and other tools.

The electric motor within the housing 10 may be of any type suitable for driving the tools, and preferably the housing is provided with a number of vents 24, at either or both ends, and 10 the motor with a small fan to cause a flow of cooling air therethrough. In some cases, the motor may be omitted and the spindle 15 connected to a flexible shaft driven from a stationary motor.

15 While I have shown and described one form of my invention, it will be apparent to those skilled in the art that it may be embodied in many other forms and modifications, and I claim all such that come within the scope of the following 20 claims:

1. In an implement of the class described, the combination of a tubular casing of sufficient length to form a hollow handle, a power unit attached to and closing one end thereof, said 25 casing near its opposite end having a side opening, a spindle journaled in said casing and driven from said power unit, and a nail treating tool mounted on said spindle within said casing and accessible through said opening.

2. In an implement of the class described, the combination of a tubular casing of sufficient length to form a hollow handle, a power unit attached to and closing one end thereof, a driven shaft therein connected to said power unit at 35 one end and journaled in and extending beyond said casing at the other end, a nail treating tool mounted on said shaft extension, a side opening in said casing, and a nail treating tool mounted on said shaft within said casing and accessible through said opening.

3. In an implement of the class described, the combination of a tubular handle having side openings near one end, a shaft journaled in said handle and extending beyond said one end, a 45 nail treating tool mounted on said extended end of the shaft, nail treating tools mounted on said shaft within said handle and accessible through said openings, and means for driving said shaft.

4. In an implement of the class described, the 50 combination of a tubular casing of sufficient length to form a handle having a side opening near one end thereof, a shaft journaled in said handle, a nail treating tool of greater width than said opening mounted on said shaft within said 55 handle and accessible through said opening, and driving means connected to the end of said shaft remote from said opening.
